COMBINED BAG LOADING TRAY AND SUPPORT

Jack E. Gruden, 16817 Ballinger St.,
Sepulveda, Calif. 91343

Filed July 15, 1971, Ser. No. 163,134

Term of patent 14 years

Int. Cl. D6—06

U.S. Cl. D6—20

FIG. 1 is a perspective view of a combined bag loading tray and support embodying my new design;

FIG. 2 is an elevational view of one side thereof;

FIG. 3 is a top plan view thereof;

FIG. 4 is a rear elevational view thereof;

FIG. 5 is an elevational view taken from the side opposite that shown in FIG. 2; and

FIG. 6 is a bottom plan view thereof.

I claim:

The ornamental design for a combined bag loading tray and support, as shown.
